CARRYING HANDLE

Morris Friedman, Fort Lee, N.J., assignor to Blockhead,
Inc., New York, N.Y., a corporation of New York

Filed Oct. 22, 1969, Ser. No. 19,671

Term of patent 7 years

Int. Cl. D8—03

U.S. Cl. D8—154

FIG. 1

FIG. 2

FIG. 3

FIG. 4

FIG. 5

FIG. 1 is a perspective view of a carrying handle embodying my new design, as viewed from the right side thereof;

FIG. 2 is a top plan view thereof on an enlarged scale;

FIG. 3 is a left-side elevational view thereof on an enlarged scale;

FIG. 4 is a rear elevational view thereof on an enlarged scale; and

FIG. 5 is a front elevational view thereof on an enlarged scale.

I claim:

The ornamental design for a carrying handle, as shown.
